UNITED STATES PATENT OFFICE.

HERBERT E. WHITE, OF YOUNGSTOWN, OHIO, ASSIGNOR TO TRUSCON STEEL COMPANY, OF YOUNGSTOWN, OHIO, A CORPORATION OF MICHIGAN.

FLOOR AND CEILING CONSTRUCTION.

Application filed March 11, 1927. Serial No. 174,588.

This invention relates to a novel and practical floor and ceiling construction particularly adapted for light building construction, where a substitute is desired for 5 all-wood construction without the expense of concrete or hollow tile.

To that end the invention contemplates a simple and practical construction wherein the wood floor is protected by a metallic 10 armor or sheathing spaced therefrom to also provide an insulating air space which renders the construction reasonably fireproof.

A further object of the invention is to provide a novel sectional metal sheathing 15 construction wherein the joints between the plates or sections are so constructed and arranged that the fastenings which secure the metal plates to the supporting element are shielded or protected from direct contact 20 with the flame or fire thereby providing increased protection at this part of the construction.

With the above and other objects in view which will more readily appear as the 25 nature of the invention is better understood, the same consists in the novel construction, combination and arrangement of parts hereinafter more fully described, illustrated and claimed.

A preferred and practical embodiment of 30 the invention is shown in the accompanying drawings in which

Figure 1 is a vertical cross-sectional view of a portion of a floor and ceiling constructed in accordance with the present invention.

Figure 2 is a vertical sectional view taken on the line 2-2 of Figure 1.

Figure 3 is a vertical cross-sectional view 40 of the modification shown in Figure 1.

Figure 4 is a vertical sectional view taken on the line 4-4 of Figure 3.

The use of the steel joists formed of 45 channel and angle sections spot-welded together has been common practice for sometime. This construction, however, has involved the use of some type of suspended ceiling or concrete floor to make the building reasonably fireproof. The underside of the 50 ceiling is always the weak spot from a fire standpoint, and the present invention aims to overcome this weakness by utilizing imperforate steel plates, sections or sheets, in place of wood lath and plaster such as com-

monly used in connection with wood construction.

Accordingly as will be observed from the drawings it is proposed to provide a construction which includes a wood floor A and a metallic sheathing B spaced therefrom to 60 provide an insulating air space C therebetween. This arrangement provides a floor and ceiling construction wherein the metallic sheathing element B may be utilized either at the top or bottom of the joists to 65 provide a protecting facing or fire guard for the floor A, as will be observed from Figures 1 and 3 for example.

Referring more particularly to Figures 1 and 2 it will be observed that the upper 70 and lower chords of the joists D are formed with the socket portions 1-1 which receive a wood or equivalent nailing strip or ground 2 which may be held in place by the turning in of the flanges at the sides of the sockets. 75 These portions are supported in the usual way in a building structure, and the upper nailing strips 2 are adapted to receive the fastenings 2' for a common wood floor 3.

The lower nailing strips 2 are adapted 80 to receive the fastenings 4 of the sheathing B as shown in Figure 2 and which constitutes the ceiling. This sheathing element B is therefore, in the present embodiment, adapted to be supported at the bottom of 85 the joists D to provide the metallic ceiling of the structure. The said sheathing B is preferably made of elongated sections 5 which are disposed cross-wise of the nailing strips 2 and are formed at their lateral 90 edges with interlocking joint portions which constitute one of the novel and distinctive features of the present invention. That is to say, one edge of each section is turned inwardly to provide a groove and supporting shoulder 6, and after coming out of the groove is continued outwardly to form an overhanging attaching or fastening flange 7.

The other or opposite edge of each section is provided with an upwardly and outwardly turned portion which provides a rib 8 for fitting in the groove formed between the shoulder 6 and the attaching flange 7 and also resting on the shoulder 6 to hold the edges of adjacent sheaths interlocked 100 and in supporting engagement.

As will be readily apparent from the drawings, a novel feature of the construction

resides in the provision of an interlocking joint wherein the adjacent plates serve as a protecting medium when the heads of the fastenings 4 pierce the attaching flanges of 5 the sections. That is to say, in installing the plates or sections 5, the same are secured to the lower nailing strips 2 by the means of the fastenings 4 penetrating the attaching flange or margin and then when 10 an adjacent sheath is put in position, the edge or joint portion thereof will conceal and protect the head of the fastening 4 from direct contact with fire and thus prevent the quick burning out of the fastening and 15 consequently dropping of the ceiling.

Figures 3 and 4 of the drawings illustrate a modification of the invention that may be resorted to, wherein the sheathing B forming the ceiling is supplemented by 20 an additional sheath or ceiling B' arranged on top of the upper nailing strips 2 to provide an additional insulating space C' beneath the floor A. In this form of construction the sections 5^a of the upper sheathing 25 B' are adapted to rest on the upper nailing strips 2 whereby the attaching flanges 7^a thereof may be secured to the strips by the fastenings 4^a. In this arrangement the heads of the fastenings 4^a will also be protected or concealed by the overlapping of the adjacent section, and the wood floor A' secured to the strips 9 which parallel the nailing strips 2 and the top chords and constituting a nailing ground for the wood 30 floor. This arrangement provides a heavier and stronger construction when desired and also furnishes additional resistance to fire by reason of providing the two air spaces 35 C and C'.
40 From the foregoing it will be apparent that the novel and distinctive characteristics of the invention are to provide a floor and ceiling construction comprising the joist members D adapted to support the wood

floor A and also carry the metallic sheathing B either at the location of the lower chords of the joist members or between the top chords thereof and the floor. In that connection it is also pointed out that the interlocking of the metal plates or sections 45 forming the sheathing is a valuable and practical structural advantage since it not only serves to reinforce the sheets at the edges but at the same time provides a construction which covers and conceals the 50 fastenings for the sheets which would otherwise be exposed.

Without further description it is thought that the features and advantages of the invention will be readily apparent to those 55 skilled in the art, and it will of course be understood that changes in the form, proportion and minor details of construction may be resorted to, without departing from the spirit of the invention and scope of the 60 appended claim.

I claim:-

A composite wood floor and metallic ceiling construction including in combination with metallic joist members having wood 70 nailing strips fitting in the top and bottom chords thereof, metallic sheathing sections having interlocking joint portions offset from the flat plane thereof, and one of said 75 portions being secured directly to and crossing the nailing strips in the top and bottom chords of the joist members and providing an insulating air space between the sheathing sections and the nailing strips, floor nailing strips arranged on top of the sheathing carried by the top chords of the joist and located at the position of said chords, and a wood floor secured to said floor nailing strips.

In testimony whereof I hereunto affix my 80 signature.

HERBERT E. WHITE.
